UNITED STATES PATENT OFFICE.

CHARLES NESSLER, OF NEW YORK, N. Y.

PROTECTIVE SHIELD FOR HAIR WAVING.

Application filed December 22, 1925. Serial No. 76,975.

My invention relates in general to the art of waving growing hair on the head which is now so extensively practiced in processes for producing a so-called permanent wave in the hair. In these processes, the coiled hair in wetted condition is inserted in an electric heater and the heat is applied and usually reaches the temperature of boiling water. With such a high degree of heat some protection had to be provided for the scalp of the head and this resulted in the heretofore use of many different forms of devices for this purpose. In many of the said prior devices, there are certain drawbacks, such as the engagement of the device with the steaming tube or the heater in more or less secure manner, thereby preventing easy and quick separation of the same; also the non-centering of the coiled hair strand in the heater, so that the hair is pressed against one side of the interior of the heater and thereby becomes overheated; and the majority of such prior devices are complicated in construction and expensive to manufacture; and furthermore many of them cannot be quickly applied and removed from operative position.

In my improved scalp protector, I seek to overcome the above stated drawbacks in this class of devices, and I provide a self-retaining device of soft absorbent material which is capable of being quickly pressed around the strand or tress of hair and thereby caused to hug the same under pressure and cling thereto in operative position, so as to form an effective closure for the heater, at the same time leaving the wound strand of hair with its curler free to center itself in the tubular heater and also free to be easily and quickly withdrawn endwise from the heater in any emergency where the hair is to be freed from the waving appliances without delay. Another important advantage of my improved device is its self-adjusting capacity under squeezing compression so that the passage way for the hair-strand is lined with soft material and hugs the hair-strand with a grip sufficient to hold the device in place, irrespective of the cross-sectional size or area of the encompassed hairstrand. Furthermore, my device is of an absorbent character readily taking up all of the liquid which might be discharged from the steaming tube or heater. There are other advantages possessed by my im-

provements which will hereinafter appear from the detailed description thereof.

I have illustrated a type of my invention in the accompanying drawings, wherein;

Fig. 1, shows a side elevation of an ordinary tubular electric-heater, with the inner or head-end broken away and a curler with a wound strand of hair thereon shown as arranged inside the heater, and my improved protector placed around the hair-strand outside of the heater and in contact with the open end thereof.

Fig. 2, shows a plan view of my protector, detached and in open condition.

Fig. 3, shows a horizontal sectional view of the improved protector and shows the disposition of the contained wire, the device being in open condition.

Fig. 4, shows a perspective view of my protector closed around a hair-strand which is shown as passing through the device.

Fig. 5, is a similar view to that in Fig. 2, but in closed condition.

Referring to the drawings, 1 indicates an ordinary tubular electric heater, in which is inserted for the purpose of waving it, a strand of hair 2, which is twisted or wound around a curler-rod 3, to which the hair-strand is secured by a tied piece of cord 4, at a point near the scalp which is indicated at 5.

My improved device, which may be considered as a combined protective pad and clip, is composed of a piece of wire 6, convoluted or twisted on itself, and which is here shown in the form of the letter W, with the central bend at 7, and the free ends turned inwardly on themselves at 8, 8, where they terminate. The various strands of the wire form are preferably all in the same horizontal plane to make it substantially flat. The central bend 7, provides a deep passage way or fork 9, for the strand of hair 2, to pass through. The wire, which may for example be made of iron, or may be ordinary fuse-wire, is flexible and is capable of retaining its distorted form or compressed position, so as to close the mouth of the fork or notch 9, when the side limbs of the W-form are compressed towards each other. The fork or jaws are opened, into the position shown in Figs. 2 and 3, by forcibly spreading the prongs apart after they have been squeezed together, as shown in Figs. 1, 4 and 5.

The wire frame 6, is covered in any suitable manner with an absorbent covering or envelope 10, which may be made of any suitable well known material, such as woven absorbent fabric, or asbestos, or asbestos-wool, or a mixture of cotton and asbestos. This jacket 10, is of substantial thickness so as to give considerable bulk and mass to the device and also to afford ample absorptive capacity for the same. This soft material 10, is here shown in the convenient form of a woven tube through which the wire is passed so that it is completely housed thereby. In constructing the device 10 the wire may be cut to length in straight condition or form and then passed into a cut length of the housing 10, and the same then bent into the peculiar W-shaped form as shown, and the central limbs secured together near one end at the points 11 and 12, (by stitching in the present instance), and near the other end at point 13, (likewise by stitching). This arrangement provides a flat pad structure which is snugly 20 closed along the lines of contact between the bent stretches of the limbs, and leaves an open gap or passage 9, into which the hair-strand is passed laterally to apply the device. The dimensions of the protector or 30 pad are such as to more than cover the open end of the heater 1, and to leave considerable of an overhang beyond the same, as indicated in Fig. 1, and the precaution is taken to have closed all joints or seams in the pad 35 which fall within the area of the mouth of the bore of the heater, in order to provide a closure for the mouth.

It will be noted that the described structure provides a pad or closure having a fork 40 of substantial size for receiving the hair-strand, so that the open device may be applied to the hair-strand by a lateral movement of the device at right-angles to the hair-strand until the latter is seated in the crotch of the fork, whereupon, the prongs 45 or jaws, indicated at 14 and 15, are squeezed together and closed, and this serves to compress the soft prongs against the hair-strand, so that it is compacted and held under the tension of this compression. This 50 seals the passage around the hair-strand and causes the pad to grip the hair-strand and maintain itself closed and in position on the hair-strand.

In Fig. 4, I show how the hair-strand extends through the pad after it is squeezed by hand into closed position. In Fig. 1, I show the pad protector as applied to the hair-strand during the waving process by 55 means of the heater 1. The pad device may be quickly mounted in place on the hair-strand, after the same is wound on and secured to the curler-rod, either before or after the heater is applied. It is placed between 60 the open end of the heater and the scalp as

shown in Fig. 1, and if preferred in some cases an additional protection may be provided by using any one of the well known forms of fiber-shields between the pad and the scalp, but I do not deem this necessary. 70

The protector is readily dismounted by seizing the prongs 14 and 15, with the fingers and spreading them open to release the confined hair-strand.

It will be observed, that the curler 3, 75 tends to center itself in the bore of the heater and when centered that the hair-strand 2, at the mouth of the bore is slightly off center. As my protector is only attached to the hair-strand, the curler is free to center 80 itself and this shifts the pad slightly to one side as indicated in Fig. 1. The protector being unattached to the heater, the device may together with the curler and wound hair-strand be easily and rapidly pulled out 85 from the heater, in case of accident, and this is particularly true with an improved form of curler devised by me and which is provided at its outer end with a yielding device which makes frictional contact with 90 the interior of the bore of the heater and also serves to center the curler at its outer end.

The soft character of the encompassing jaws of the device also protect the surrounded strand of hair from mutilation in addition to making a close fit around the same, when gripped in place. The pliability of the clamping parts of the protector is such that they may be easily squeezed by hand 100 into closed position around the hair strand and it automatically fits the strand whether it be of small or large cross-sectional area.

The wire may be of any suitable well known material which will not spring back 105 when distorted and as the device may be used more than once without destruction, it is advisable to use a rustless wire, and copper or a suitable alloy may be employed.

Having thus described my invention, what 110 I claim and desire to secure by Letters Patent is:—

1. A scalp protector for use in waving hair on the head by means of a heater in which a strand of hair is placed for a heating operation, comprising a disk of substantial heat-screening area of soft material having embedded therein a member capable of being bent or distorted and of retaining its distortion, said device being constructed to receive through it a tress of hair and being adapted to be compressed around the same circumferentially thereof and squeeze the hair and retain itself in place.

2. A scalp protector for use in waving 125 hair on the head by means of a heater in which a strand of hair is placed for a heating operation, comprising a tubular fabric and a flexible wire disposed therein and covered thereby and formed into a substan- 130

tially flat body of an external diameter not substantially less than that of the abutting end of the heater and capable of being bent around a strand of hair in gripping contact therewith and normal thereto and retain itself in place thereon.

3. A scalp protector for use in waving hair on the head by means of a heater in which a strand of hair is placed for a heating operation, comprising pliable absorbent material wholly or partly made of asbestos, and forming a flat body of substantial heat-screening surface and a flexible member arranged in said material and capable of being bent and retaining its bent form, said device being formed with jaws for receiving a strand of hair therein, said wire being arranged to close said jaws circumferentially around the contained hair-strand when the jaws are compressed.

4. A scalp protector for use in waving hair, comprising a flexible wire covered with absorbent material and formed W-shaped substantially so that the central bend thereof provides a deep fork the prongs of which are adapted to encompass a strand of hair.

5. A scalp protector for use in waving

hair on the head by means of a heater in which a strand of hair is placed for heating operation, consisting in a substantially flat compressible body of substantial heat-screening area and provided with a hair-strand receiving opening and capable of being forcibly compressed circumferentially around the inserted hair-strand and of retaining it- 35

6. A scalp protector for use in waving hair on the head by means of a heater in which a strand of hair is entered for heat treatment, comprising a practically flat compressible body having a comparatively large heat-screening area and provided with an opening for receiving laterally therein a hair-strand and capable of being squeezed around the contained hair-strand circumferentially thereof and then retaining itself thereon by gripping action, the said body being absorbent and having capacity to take up a substantially amount of fluid escaping from the heater. 50

In testimony whereof, I have hereunto set my hand.

CHARLES NESSLER.
